DIE RETAINER

Andrew O. McCollum, Detroit, Mich.

Application June 4, 1943, Serial No. 489,648

1 Claim. (Cl. 164—124)

This invention relates to punches and dies, and more particularly to retainers therefor.

Broadly the invention comprehends a punch or die retainer of simplified structure.

An object of the invention is to provide a retainer for a punch or die so constructed as to effectively retain the punch or die against displacement regardless of the stresses imposed thereon in the normal uses thereof.

Another object of the invention is to provide a punch or die retainer of the character designated in which the amount of required machine operation on the parts during manufacture thereof shall be materially reduced.

A still further object of the invention is to provide a punch or die retainer which has the advantages of a positive lock for the punch or die, is highly efficient in operation and yet of marked simplicity as a whole and in respect to each of its component parts to the end that its manufacture may be economically facilitated both as regards to parts and their assembly.

Other objects and structural details will be apparent from the subjoined description taken in connection with the accompanying drawings forming a part of this specification, and in which—

Fig. 1 is a vertical view, partly in section and partly in elevation, illustrating an assembly of a punch and die.

Fig. 2 is an enlarged view mostly in section illustrating a retainer secured to the working head of a punching machine with a punch locked therein;

Fig. 3 is a sectional view substantially on line 3—3, Figure 2;

Fig. 4 is an end view of the retainer and punch;

Fig. 5 is a vertical sectional view partly in elevation illustrating a modification of the invention; and

Fig. 6 is a vertical sectional view partly in elevation illustrating another modification of the invention.

Referring to the drawings for more specific details of the invention, 10 represents the ram of a conventional punching machine. The ram has secured thereto as by machine screws 12 a block or cylindrical member 14 of suitable hardness and finish. The block has a central or concentric bore 16, and fitted in the wall of the block adjacent the back thereof is a centering pin 18 having a portion of its perimeter extended into the bore 16.

The block or cylindrical member 14 also has a bore 20 therein inclined from the face of the

member inwardly and opening into the bore 16. The bore 20 is partly threaded, as indicated at 22, and mounted for travel in the bore 20 is a lock pin 24 having a threaded portion 26 for co-operation with the threads 22 and a smoothly finished portion fitted snugly in the bore 20 and terminating in a cone-shaped free end 28, and the outer or exposed end of the lock-pin is slotted as at 30 for the reception of a hand tool.

10 A punch 32 has a shank 34 provided with a circumferential slot 36 extended parallel to the axis of the punch and a recess 38 extended from the perimeter of the shank inwardly thereof and toward the butt of the shank. The recess 38 is 15 defined by a wall portion complementary to the bore 20 and a shoulder portion 40 complementary to the conical end of the lock-pin.

The lock-pin is backed outwardly until the pin is fully retracted from the bore 16. The shank 20 of the punch is then inserted in the bore with the circumferential slot 36 in the shank receiving the centering pin 18. This aligns the recess 38 with the bore 20 in the retainer member 14. The lock-pin is then turned down until the conical end 26 thereon engages the shoulder 40. This provides a smooth bearing between the shank and the lock-pin, and thus facilitates in moving the shank against the ram with force and in retaining the punch against displacement.

30 A die shoe 42 has mounted thereon a retaining member 44 corresponding to the retaining member 14. The member 44 has a concentric bore 46, and threaded in the wall of the member 44 is a lock-pin 48 corresponding to the lock-pin 24.

35 A die 50 fitted in the bore 46 has a recess 52 in its circumference for the reception of the lock-pin 48 and a concentric bore 54 for the reception of the punch. The bore 54 has a portion 56 adjacent the face of the die of uniform cross-section, 40 and a portion of varying cross-section increasing gradually from the portion of uniform cross-section to the base of the die.

45 A modification of the retainer is illustrated in Fig. 5. In this modification a lock-pin 124 corresponding to the lock-pin 24 in the preferred embodiment of the invention has a free end portion terminating in a rounded end 126, and the shank of the punch has a recess complementary to the free end of the pin.

50 Another modification of the invention is illustrated in Fig. 6. In this embodiment of the invention a lock-pin 224 has a free end portion terminating in a flat end 226, and the shank of the punch has a recess complementary to the free end of the pin.

While this invention has been described in connection with certain specific embodiments, the principle involved is susceptible of numerous other applications that will readily occur to persons skilled in the art. The invention is, therefore, to be limited only as indicated by the scope of the appended claim.

Having thus described the various features of the invention, what I claim as new and desire to secure by Letters Patent is:

A die retainer comprising a cylindrical body

having a concentric bore therethrough and a partly threaded bore inclined from the face of the body inwardly to and in communication with the concentric bore, a centering pin in the body parallel to the vertical axis thereof and adjacent the top of the body having a part of its peripheral area extended into the concentric bore, and a lock-pin mounted for travel in the inclined bore having an accessible head slotted for the reception of a hand tool and a finished conical end.

ANDREW O. MCCOLLUM.
